INSTRUMENT PANEL LIGHTING

Manfred Muenz, Syosset, N.Y., assignor to Loral Electronics Corporation, New York, N.Y., a corporation of New York

Filed Apr. 18, 1961, Ser. No. 103,843

2 Claims. (Cl. 240—8.16)

This invention relates generally to the field of instrument panel lighting, and more particularly to extremely compact forms thereof, suitable for use in conjunction with military air-borne installations.

With the increased complexity of instrument panels, there has been an accompanying attempt to miniaturize the lighting components used in conjunction therewith. Small baseless type incandescent lamps have been developed which are sufficiently small that they may be disposed within the space afforded by adjacent arcuate faces of closely spaced instruments.

To simplify wiring requirements, it has been normal practice to wire such small incandescent lamps in series, so that should the filament of one such lamps fail it becomes necessary to individually test each of the lamps by replacing it with a new one until the faulty lamp is found. As such lamps are normally mounted from the rear of the panel, they are not readily accessible, and the removal of the lamps calls for considerable manual dexterity as well as the use of special tools.

It is therefore among the principal objects of the present invention to provide an improved instrument panel lighting system, in which the above-mentioned disadvantages have been substantially eliminated.

Another object of the invention lies in the provision of instrument panel lighting construction which may be readily assembled and disassembled without resort to other than ordinary tools, and with the use of but ordinary skill.

Still another object of the invention lies in the provision of improved instrument panel lighting system wherein all of the incandescent lamps may be removed from the instrument panel in a single operation, whereby each of the same may be individually tested for defects without removal from association with a removable element of the instrument panel.

Still another object of the invention lies in the provision of improved instrument panel lighting systems in which the cost of fabrication may be of a reasonably low order, with consequent wide sale, distribution and use.

A further object of the invention lies in the provision of an instrument panel lighting system in which the individual lamps are positively locked in oriented position when in installed condition, but which nevertheless are readily disengaged as desired for convenient replacement.

Still another object of the invention lies in the provision of an instrument panel lighting system having increased packing density, that is to say a greater condensation of operative components, with a consequent reduction of weight and space in relation to the number and size of the components employed.

A feature of the invention lies in the provision of an improved lamp-supporting unit adapted to completely encapsulate standard instrument lighting lamps, whereby the replacement of an individual lamp does not require physical contact with the lamp itself.

Another feature of the invention lies in the provision of a lamp housing which serves both as a protective envelope for a lamp disposed therein, and as a light filter where required.

These objects and features, as well as other incidental ends and advantages, will more fully appear in the pro-

2

ress of the following disclosure, and be pointed out in the appended claims.

In the drawing, to which reference will be made in the specification, similar reference characters have been employed to designate corresponding parts throughout the several views.

FIGURE 1 is an exploded view in perspective of an embodiment of the invention.

FIGURE 2 is an exploded view in perspective of a lamp housing element which comprises a part of the embodiment.

FIGURE 3 is an enlarged fragmentary vertical sectional view as seen from the plane 3—3 in FIGURE 1.

FIGURE 4 is a side elevational view of a lamp housing element.

FIGURE 5 is a bottom plan view of a lamp housing element.

FIGURE 6 is an enlarged sectional view of an alternate form of the first embodiment.

FIGURE 7 is an offset sectional view as seen from the plane 7—7 in FIGURE 6.

FIGURE 8 is a vertical sectional view as seen from the plane 8—8 in FIGURE 7.

FIGURE 9 is a bottom plan view of a lamp housing in accordance with the alternate form of the invention.

FIGURE 10 is an end elevational view as seen from the righthand portion of FIGURE 9.

FIGURE 11 is a side elevational view as seen from the lower portion of FIGURE 9.

FIGURE 12 is an enlarged fragmentary sectional view showing a second embodiment of the invention.

FIGURE 13 is a fragmentary bottom plan view thereof.

FIGURE 14 is an exploded sectional view showing the structure of FIGURE 12 in disassembled condition.

In accordance with the first embodiment of the invention, the device, generally indicated by reference character 10, comprises broadly: a base lamina 11 which may be part of a larger panel, mounting other groups of instruments, a printed circuit lamina 12, a lamp-supporting lamina 13 and a plurality of lamp-housing elements 14.

The base lamina 11 may be of any desired configuration, and preferably formed of metallic material which is coated to render it insulative. It is bounded by peripheral edges 17, 18, 19 and 20, and includes an upper planar insulated supporting surface 21. Connecting prongs 22 and 23 extend outwardly of the planar surface 21 and provide means for interconnecting electrical current with the printed circuit lamina 12. Lock nut means 24 and 25 also extend outwardly of the upper planar supporting surface 21, the purpose of which will more fully appear at a point later in the disclosure. A pair of bored openings 26 and 27 are provided at suitable locations to accommodate either instrument faces (not shown) or control knobs of well known type.

The printed circuit lamina 12 is preferably formed of thin insulative synthetic resinous material, as, for example, the well known impregnated textiles, and the like. It includes a lower surface (not shown), an upper surface

33, and is bounded by peripheral edges 34, 35, 36, 37, 38 and 39, which form notches 40 and 41 for engagement by the lock nuts 24 and 25. The openings 42 and 43 correspond to the openings 26 and 27 in the base lamina 11. Disposed on the upper surface 33 are first, second, third and fourth printed circuit strips 44, 45, 46 and 47, respectively, which are formed by deposition of metallic materials in accordance with any of several methods well known in the art.

The first printed circuit strip 44 is generally rectilinear in configuration, including a first terminal 48 having an opening 49 for engagement with the prong 22, as well as a generally elongated portion 50 and a second enlarged

70

terminal 57. The second printed circuit strip 45 includes first and second terminals 53 and 54 interconnected by first and second elongated portions 55 and 56. The third printed circuit strip 46 includes first and second terminals 58 and 59, respectively, as well as first, second and third elongated portions 60, 61 and 62, respectively. The fourth printed circuit strip 47 generally resembles the first strip 44, including first and second terminals 64 and 65, respectively, interconnected by an elongated portion 66. An opening 67 provides for engagement with the prong 23 in a similar manner.

The lamp-supporting lamina 13 is of over-all configuration corresponding to that of the printed circuit lamina 12. It includes a lower surface 69, an upper surface 70, and is bounded by peripheral edges 71, 72, 73, 74, 75 and 76, the last-mentioned four edges forming notches 77 and 78. The bores 79 and 80 correspond in location and in dimension to the previously described bores 26, 27, 42 and 43. Positioned directly above the enlarged terminals interconnecting the printed circuit strips 44-47 are smaller bores 81, 82 and 83 of generally similar configuration, each including a keyway 84 and a countersunk portion 85 (see FIGURE 3) extending inwardly from the lower surface 69.

The individual lamp-housing elements 14 are generally similar, and accordingly a detailed description of one of said elements will serve to describe all. Referring to FIGURE 2 in the drawing, each lamp-housing element 14 includes a main housing member 86, a standard military specification incandescent lamp 87 including a glass envelope 88 and electrical leads 89 and 89', and a cover member 91.

The housing 86 is preferably molded from a suitable transparent synthetic resinous thermoplastic or thermosetting material, and includes an outer planar wall 94, and a cylindrical continuous side wall 95. Disposed upon the outer surface of the side wall 95 is a projecting key member 97 engageable within a keyway 84 as best seen in FIGURE 4 in the drawings.

The cover member 91 is preferably of synthetic resinous material, and includes an upper surface 102, a lower surface 103, and an arcuate peripheral edge 104 having a bead. Extending through the plane of the cover member 91 are a pair of bores 107 and 108 in which the electrical leads 89 and 89' are soldered or otherwise suitably fixed. Extending downwardly from the lower surface 103 are a pair of resilient contact members 109 and 110, preferably formed of brass or similar material, the same having terminal portions 111 positioned apart a distance to directly overlie the terminals of the printed contact strips 44-47 when the device 10 is assembled. The contact members 109 and 110 may be secured to the lower surface 103 of the member 91 by insert-molding, soldering, welding to an insert, or by means of headed-over rivets, grommets, or the like (not shown).

As best seen in FIGURE 4, it will be observed that the upper surface 102 of the cover 91 is partially notched to accommodate the configuration of the lamp 87, so that when the element 14 is assembled the bulb will be maintained substantially immobilized. If desired, the lamp 87 may be bonded to the upper surface 102, using a cementitious material. The notch, generally indicated by reference character 113, may be also duplicated in the under surface of the outer wall 94 as indicated by reference character 114.

The device 10 is assembled substantially as indicated in FIGURE 1, wherein the lamp-housing elements 14 are inserted and positioned within the corresponding bores 81-83, the engagement of the keys 98 within the keyways 84 serving to align the contact members 109-110 with the respective printed circuit strips 44-47. The laminae 11 and 12 are then positioned upon the lamina 13, and the nut means 24-25 is tightened to maintain the electrical connections in contact. During this assembly, the connecting prongs 22 and 23 will enter the corresponding

bores in the printed circuit strips 44 and 47, respectively, thereby forming a continuous circuit in series through the lamp-housing elements 14. Since the lamps 87 are wired in series, or in groups of series connections, the failure of any one of the same will cause all of the lamps in any one series to be extinguished. On this occurrence, the nut means 24-25 may be loosened, permitting the lamp-supporting lamina 13 to be removed. Inverting the same exposes the contact members 109-110 of each of the lamp-housing elements 14, permitting them to be individually tested without removing them from engagement with the lamp-supporting lamina 13. Upon the discovery of the defective lamp, the entire housing element 14 enclosing the same may be removed by merely manually pushing upon the outer wall 94, following which a replacement may be made and the device 10 again reassembled. In this manner, no tools are required for use in conjunction with any part of the above operation, and the reinsertion of a fresh lamp-housing requires only the alignment of the key and keyway followed by manual pressure upon the exposed surface of the cover member 91.

Turning now to the alternate form of the first embodiment of the invention, as illustrated in FIGURES 6 and 7 in the drawings, parts corresponding to those of the principal form have been designated by similar reference characters with the additional suffix "a."

The alternate form of the first embodiment differs from the principal form in the construction of the base 11a, particularly in the elimination of the pins 22 and 23 of the first embodiment by a resilient interconnecting means 22a. As best seen in FIGURE 6, the structure 22a includes a cylindrical body 120 having an outer surface 121 force-fitted or resiliently fitted within a bore 122 in the lamina 11a. Where the latter is employed, a resilient snap ring means 123 maintains the body 120 in position. Referring to FIGURE 8, the body is provided with a centrally disposed cylindrical bore 124 and a counterbore 125 in which a resilient tongue 126 is disposed. Spring means 127 urges the tongue 126 upwardly, the upward most limit of movement being determined by the engagement of a snap ring 123 with a portion of the body 120. During assembly of the alternate form, the uppermost surface 129 of the tongue 126 is engaged by the member 43a, and electrical contact is maintained in a resilient manner.

As seen in FIGURES 9, 10 and 11, the alternate form of the invention also differs from the principal form in that the lamp housing element 14a is oblong in shape rather than cylindrical, and the edge 104a which forms the bead is discontinuous, and confined to the end portions of the housing 114a. As the output of the lamp 87a is greater at the end thereof opposite the leads 89a and 89'a, indicia means 135 in the form of a painted spot may be provided as a substitute for the keying means 84-97 of the first embodiment.

Turning now to the construction shown in FIGURES 12 to 14, inclusive, parts corresponding to those of the first embodiment have been designated by similar reference characters with the additional prefix "2."

In this construction, the housing element 214 has been modified to eliminate the cover member 91, and substitute thereat a resinous conformal coating 142. If desired, coloring pigments may be introduced into the resinous material to provide a filtering action. This construction is of an over-all height somewhat less than that of the first embodiment, and accordingly it is possible to install the same in a lamina 213 which has a continuous outer surface 270.

To retain the lamp-housing element 214 in condition, a snap-ring 144 is provided which is permanently secured within a recess 146 in the lamina 213. Projecting tongues 148 and 150 are adapted to engage the edge 204 as shown in FIGURE 13, there being a plurality of recessed portions 152 permitting the entry of a tool 154 to exert a prying action whereby the lamp-housing is disengaged.

It may thus be seen that I have invented novel and

highly useful improvements in instrument panel lighting, in which the entire lighting system of an instrument panel may be subdivided into relatively small components, each containing a relatively few number of lamps in series and parallel, it being possible to readily test any or all of the lamps in a given group without difficulty, and equally easy to replace any defective lamp. By constructing substantially all of the components from synthetic resinous materials, the devices may be of light weight and of low manufacturing cost.

I wish it to be understood that I do not consider the invention limited to the precise details of structure shown and set forth in this specification, for obvious modifications will occur to those skilled in the art to which the invention pertains.

I claim:

1. In an instrument panel lighting construction, a first lamp-supporting lamina having at least one opening therein, a second lamina having electrical circuit-completing means thereon, a lamp housing selectively disposed entirely within said opening in said first lamina, said housing having illumination means disposed therein the principal axis of which is parallel to the plane of said first lamina and electrical contacting means on an outer surface thereof, said first lamina overlying said second lamina with said contacting means engaging said circuit-completing means, said opening in said first lamina including a counterbored portion, said lamp housing including a corresponding annular bead for preventing passage of said housing completely through said opening, 30

said counterbore having a recess therein for the entry of a tool, whereby said housing may be readily dislodged from contact within said opening.

5 2. In an instrument panel lighting construction, a lamp-supporting lamina having at least one opening therein, resilient means disposed within said opening, and a lamp housing selectively positioned within said opening to engage said resilient means; said housing comprising: a generally planar wall, a lamp disposed in contact with said wall and having electrical leads extending through said wall, and having contact members electrically connected to said leads and disposed outwardly of said wall, and coated translucent means enclosing said lamp and forming a seal with said wall wherein said lamp is completely encapsulated.
